UNITED STATES PATENT OFFICE

116,779

DESIGN FOR A BADGE OR THE LIKE

Walter Kuenstner, Queens Village, N. Y.

Application April 27, 1939, Serial No. 84,639

Term of patent 3½ years

To all whom it may concern:

Be it known that I, Walter Kuenstner, a citizen of the United States, residing at Queens Village, in the county of Queens and State of New York, have invented a new, original, and ornamental Design for a Badge or the like, of which the following is a specification, reference being had to the accompanying drawing, forming a part thereof.

Figure 1 is a plan view of a badge showing my new design, Figure 2 is an end elevational view of the design. The dominant features of the design are shown in full lines.

The drawing has been ruled for color.

I claim:

The ornamental design for a badge or the like, as shown and described.

WALTER KUENSTNER.
